UNITED STATES PATENT OFFICE.

FREDERICK OTTO MINER, OF CRAFTON, PENNSYLVANIA.

BUOY.

1,091,860.

Specification of Letters Patent. Patented Mar. 31, 1914.

Application filed August 25, 1913. Serial No. 786,536.

To all whom it may concern:

Be it known that I, FREDERICK OTTO MINER, a citizen of the United States, residing at Crafton, in the county of Allegheny and State of Pennsylvania, have invented certain new and useful Improvements in Buoys, of which the following is a specification.

This invention relates to improvements in buoys and has for its object to provide a buoy adapted to indicate the location of a sunken vessel.

Another object of the invention is to provide a combined buoy, oil dispensing device and receptacle for foods, water and pyrotechnical signaling devices.

Still another object of the invention is to provide a traveling buoy adapted to carry a life line from a wrecked vessel to shore.

Another object of the invention is to provide a series of buoys having means whereby they are held in direct connection with a sunken vessel.

With the above and other objects in view which will be more fully explained in the following specification, I have invented the device illustrated in the accompanying drawings in which—

Figure 1 is a side elevational view of a sunken vessel showing my invention in operative connection therewith. Fig. 2 is an enlarged elevational view of a buoy. Fig. 3 is a detail top plan of a cradle. Fig. 4 is a section on line A—A, Fig. 2 and Fig. 5 is a view similar to Fig. 4 but shown in a disassembled position.

Like reference characters indicate like parts throughout the specification and in the several views in the drawings in which—
1 indicates steam ship which has sunken to a position of approximately 4000 feet below the surface of the sea, and 2, 3 and 4 are buoys connected to said vessel. The construction and operation of these buoys all being the same only one will be described.

The buoy 2 is a bell buoy having a bell 5 mounted upon the apex 6 of the dome 7 by means of the frame 8. This bell buoy is divided into an upper compartment 9, which is adapted to hold fresh water for drinking purposes and a lower compartment is filled with compressed air and a series of smaller compartments 11 which are adapted to hold compressed food and skyrockets or other distress signaling devices, matches, etc.

12 is a screw cap forming a closure for the opening 14 into the water compartment 9 and 13 are closures for the compartment 11.

The bottom wall 15 of the member 2 is concave so as to seat upon the convex top 16 of the chamber 17 said chamber having extending side walls 18, having openings 19 therein. The walls form a cradle in which the buoy 2 normally rests. The openings 19 being adapted to admit water into said cradle when the buoy 2 floats out this preventing suction from holding said buoy against free movement.

Within the chamber 17 is mounted upon bearings 20 and 21 a freely rotatable drum 22 upon which is wound a cable 23 one end 24 of which is fixed to the central part of the wall 15 so that when the buoy 2 floats and the vessel 1 sinks, the cable 23 will be gradually unwound. The chamber 17 is kept filled with oil 25. This oil performs the double function of keeping the cable from rusting and gradually seeping out through the cable opening 26 after the vessel sinks and rising to the surface of the water and calming the same.

The bottom wall 27 of the chamber 17 forms a top wall for the air chamber 28. This chamber is also filled with compressed air and its wall 29 is semi-spherical so as to seat snugly into the similarly shaped cradle 30. This cradle is also provided with openings, marked 31. The cradle 30 is mounted upon a tubular support 32 which connects with the chamber 33. Mounted within the chamber 33 is a spindle 34 upon which is freely rotatably mounted a drum 35 upon which is wound the cable 36 the upper end 37 of which passes through the tube 32 and it is fixed to the wall 29, and the other end 38 of which is fixed to the center of a disk 39 which is provided with perforations 40. When the cable 36 is entirely unwound from the drum 35 and is drawn through the tube 32, the disk 39 engages the wall 41 of said chamber 33 and holds said cable 36 fixed to said wall 41. The perforations 40 permit oil, with which said chamber 33 is kept filled to pass through the tube 32 whereby the oil will float to the surface of the water and calm the same and thus the water directly over the place where the vessel is sunk will be calmed. The oil, having an affinity for metal, will remain in the water near the

buoys and keep the sea calm over the sunken vessel, thus permitting persons to cling to the bell buoys with less danger of being washed away and also permitting them to get at the water, and provender in the compartments and to fire off sky rockets from the support 42 formed on the outer surface of said bell buoy for the purpose. A series of ropes 45 are provided having loops 47 fixed to the flange 46 whereby persons may secure themselves to said bell-buoys.

The bottom wall 43 of the chamber forming box 44 will be securely fixed to the vessel so that it cannot accidentally become removed. Should the vessel reach the bottom of the sea and careen to one side the tube 32 will be broken by the force of the air tanks 10 and 28 pulling on the cable 36 thus permitting said cable to entirely unwind if necessary.

The device operates as follows:—When a vessel sinks the member 28 floats, the cable 36 gradually unwinding as the vessel goes down until the entire cable is spent after which said compartment or air tank 28 is held in a relative position to the vessel according to the length of the cable, which may be several thousand feet. After the cable 36 has unwound its entire length the bell-buoy 2 begins to float from its cradle and the cable (which is of a smaller thickness than the cable 36) begins to unwind until the vessel stops going down, the bell-buoy remains floating on the surface of the water. Persons floating or in boats may readily reach the bell-buoys to get water and food or signals. The oil arising from the oil tanks 33 and 17 will keep the surface of the water around said buoys calm.

Should a vessel become stranded on the rocks, the bell-buoy can be removed from its cradle and cast upon the water and the waves will carry it to shore and the cable 23 with it this will act as a life line, by means of which persons on the vessel may be carried ashore.

Each of the buoys 2, 3 and 4 are painted different colors in order that it may be determined from the color of the buoy which is the stern and which is the bow of the vessel.

Having now described my invention that which I desire to procure by Letters Patent is:—

1. In combination with a vessel, an oil containing tank therein, a buoy mounted over said tank and a drum having a cable wound thereon in said tank and connected to said buoy.

2. In combination with a vessel, an oil containing tank therein, a buoy mounted over said tank, a drum having a cable wound thereon in said tank and connected to said buoy, said tank having an opening through which said cable may pass and means for nearly closing said opening.

3. The described device consisting of a buoy having means whereby it may be secured to the vessel, said means consisting of a cable connecting said buoy and said vessel, a drum upon which said cable may be wound, and an oil container in which said drum is mounted.

4. The described device consisting of a buoy having means whereby it may be secured to the vessel, said means consisting of a cable connecting said buoy and said vessel, a drum upon which said cable may be wound, and an oil container in which said drum is mounted, and a cradle mounted upon said container in which said buoy is adapted to seat.

5. The described device consisting of a buoy having means whereby it may be secured to the vessel, said means consisting of a cable connecting said buoy and said vessel, a drum upon which said cable may be wound, an oil container in which said drum is mounted, a cradle mounted upon said container in which said buoy is adapted to seat, and said buoy having an air compartment and an oil containing compartment.

6. The described device consisting of a buoy having means whereby it may be secured to the vessel, said means consisting of a cable connecting said buoy and said vessel, a drum upon which said cable may be wound, an oil container in which said drum is mounted, a cradle mounted upon said container in which said buoy is adapted to seat, said buoy having an air compartment and an oil containing compartment, and an additional buoy connected to said first buoy.

7. The described device consisting of a buoy having means whereby it may be secured to the vessel, said means consisting of a cable connecting said buoy and said vessel, a drum upon which said cable may be wound, an oil container in which said drum is mounted, a cradle mounted upon said container in which said buoy is adapted to seat, said buoy having an air compartment and an oil containing compartment, an additional buoy connected to said first buoy, and a cable forming said latter connection.

8. The described device consisting of a buoy having means whereby it may be secured to the vessel, said means consisting of a cable connecting said buoy and said vessel, a drum upon which said cable may be wound, an oil container in which said drum is mounted, a cradle mounted upon said container in which said buoy is adapted to seat, said buoy having an air compartment and an oil containing compartment, an additional buoy connected to said first buoy, a cable forming said latter connection, and a drum upon which said latter cable may be wound.

9. The described device consisting of a buoy having means whereby it may be secured to the vessel, said means consisting of

5 a cable connecting said buoy and said vessel, a drum upon which said cable may be wound, an oil container in which said drum is mounted, a cradle mounted upon said container in which said buoy is adapted to seat, said buoy having an air compartment and an oil containing compartment, an additional buoy connected to said first buoy, a cable forming said latter connection, a drum upon which said latter cable may be wound, and said drum mounted in said oil compartment in said buoy.

10 10. The described device consisting of a buoy having means whereby it may be secured to the vessel, said means consisting of a cable connecting said buoy and said vessel, a drum upon which said cable may be wound, an oil container in which said drum is mounted, a cradle mounted upon said container in which said buoy is adapted to seat, said buoy having an air compartment and an oil containing compartment, an additional buoy connected to said first buoy, a cable forming said latter connection, a drum upon which said latter cable may be wound, and said drum mounted in said oil compartment in said buoy, and a cradle on said first buoy within which said second buoy may seat.

15 11. The described device consisting of a buoy, having means whereby it may be secured to the vessel, said means consisting of a cable connecting said buoy and said vessel, a drum upon which said cable may be wound, an oil container in which said drum is mounted, a cradle mounted upon said container in which said buoy is adapted to seat, said buoy having an air compartment and an oil containing compartment, an additional buoy connected to said first buoy, a cable forming said latter connection, a drum upon which said latter cable may be wound, said drum mounted in said oil compartment in said buoy, a cradle on said first buoy within which said second buoy may seat, and said second buoy having an air compartment and a fresh water compartment.

20 12. The described device consisting of a buoy having means whereby it may be secured to the vessel, said means consisting of a cable connecting said buoy and said vessel, a drum upon which said cable may be wound, an oil container in which said drum is mounted, a cradle mounted upon said container in which said buoy is adapted to seat, said buoy having an air compartment and an oil containing compartment, an additional buoy connected to said first buoy, a cable forming said latter connection, a drum upon which said latter cable may be wound, said drum mounted in said oil compartment in said buoy, a cradle on said first buoy within which said second buoy may seat, and said second buoy having an air compartment and a fresh water compartment.

25 ment, and a plurality of other compartments.

13. The described device consisting of a buoy having means whereby it may be secured to the vessel, said means consisting of a cable connecting said buoy and said vessel, a drum upon which said cable may be wound, an oil container in which said drum is mounted, a cradle mounted upon said container in which said buoy is adapted to seat, said buoy having an air compartment and an oil containing compartment, an additional buoy connected to said first buoy, a cable forming said latter connection, a drum upon which said latter cable may be wound, said drum mounted in said oil compartment in said buoy, a cradle on said first buoy within which said second buoy may seat, said second buoy having an air compartment and a fresh water compartment, a plurality of other compartments, and a bell mounted upon said second buoy.

30 14. The described device consisting of a buoy having means whereby it may be secured to the vessel, said means consisting of a cable connecting said buoy and said vessel, a drum upon which said cable may be wound, an oil container in which said drum is mounted, a cradle mounted upon said container in which said buoy is adapted to seat, said buoy having an air compartment and an oil containing compartment, an additional buoy connected to said first buoy, a cable forming said latter connection, a drum upon which said latter cable may be wound, said drum mounted in said oil compartment in said buoy, a cradle on said first buoy within which said second buoy may seat, said second buoy having an air compartment and a fresh water compartment, a plurality of other compartments, and a bell mounted upon said second buoy, and said second buoy having a pocket formed on its outer surface.

35 15. The described device consisting of a buoy having means whereby it may be secured to the vessel, said means consisting of a cable connecting said buoy and said vessel, a drum upon which cable may be wound, an oil container in which said drum is mounted a cradle mounted upon said container in which said buoy is adapted to seat, said buoy having an air compartment and an oil containing compartment, an additional buoy connected to said first buoy, a cable forming said latter connection, a drum upon which said latter cable may be wound, said drum mounted in said oil compartment in said buoy, a cradle on said first buoy within which said second buoy may seat, said second buoy having an air compartment and a fresh water compartment, a plurality of other compartments, a bell mounted upon said second buoy, and said second buoy having a pocket formed on its outer surface.

surface, and a plurality of cables connected to said second buoy.

16. The described device consisting of a buoy having means whereby it may be secured to the vessel, said means consisting of a cable connecting said buoy and said vessel, a drum upon which said cable may be wound, an oil container in which said drum is mounted, a cradle mounted upon said container in which said buoy is adapted to seat, said buoy having an air compartment and an oil containing compartment, an additional buoy connected to said first buoy, a cable forming said latter connection, a drum upon which said latter cable may be wound, said drum mounted in said oil compartment in said buoy, a cradle on first buoy within which said second buoy may seat, said second buoy having an air compartment and a fresh water compartment, a plurality of other compartments, a bell mounted upon said second buoy, said second buoy having a pocket formed on its outer surface, a plurality of cables connected to said second buoy, and said cables having loops at their outer ends.
17. In combination with a vessel, an oil containing tank therein, a buoy mounted over said tank, a drum having a cable wound thereon in said tank and connected to said buoy, said tank having an opening

through which said cable may pass, and means for nearly closing said opening, said means consisting of a disk on one end of said cable.

18. In combination with a vessel, an oil containing tank therein, a buoy mounted over said tank, a drum having a cable wound thereon in said tank and connected to said buoy, said tank having an opening through which said cable may pass, means for nearly closing said opening, said means consisting of a disk on one end of said cable, and another buoy connected to said first buoy.

19. In combination with a vessel, an oil containing tank therein, a buoy mounted over said tank, a drum having a cable wound thereon in said tank and connected to said buoy, said tank having an opening through which said cable may pass, means for nearly closing said opening, said means consisting of a disk on one end of said cable, and another buoy connected to said first buoy, said last buoy being painted a distinctive color whereby its position on a vessel may be determined.

In testimony whereof I affix my signature in presence of two witnesses.

FREDERICK OTTO MINER.
